UNITED STATES PATENT OFFICE.

JAMES K. DUGDALE AND CORNELIUS E. MASTIN, OF RICHMOND, INDIANA.

LAST AND STAND.

SPECIFICATION forming part of Letters Patent No. 403,927, dated May 28, 1889.

Application filed March 21, 1888. Serial No. 268,046. (No model.)

To all whom it may concern:

Be it known that we, JAMES K. DUGDALE and CORNELIUS E. MASTIN, citizens of the United States, residing at Richmond, in the 5 county of Wayne and State of Indiana, have invented a new and useful Improvement in Iron Last-Stands, of which the following is a specification.

The nature of this improvement consists in 10 appliances, in connection with stands, by which various sizes of iron or wood shoe-lasts are attached or detached at pleasure and firmly held in various positions while in use, the mechanism of which is illustrated in the accompanying drawings, making a part of this 15 specification, in which similar letters of reference indicate corresponding parts.

Figure 1 is a perspective view; Fig. 2, a vertical section, Figs. 3 and 4 being enlarged 20 parts.

Letter A, Fig. 1, is a stand or column supporting the device for holding the last C. B is the base of stand. D D are ears attached to stand A. Between these ears a rotating or 25 oscillating head, E, is inserted, to which head last C is attached. This stand may be in the form of a hollow tube made in two parts and bolted together, as at a a a.

Fig. 2 is a vertical section on the same 30 scale as Fig. 1, showing the position of the various parts. A is the stand or column; B, the base. E is the head to which last C is attached. This head is of a circular form, with projections forming shoulders O O in 35 front and rear, making a solid bed for the last C to rest upon. m m are beveled cleats to a notch in said head, between which cleats a beveled lug, H, attached to the last C, is inserted, which dovetails the head E and last C 40 together, so that the last may be slipped on the head or off of it at pleasure. A notch, G, is made in one of the ears D, to admit the lug H on last C to pass into the notch in head E. Then by turning the dovetailed parts slightly 45 up between the ears D D the last C and head E are locked together both ways.

J J are notches or corrugations in the periphery of head E.

K is a sliding rod, the head of which slides 50 in the stand A, and is provided with notches

to correspond with and fit into the notches J in head E.

L is an eccentric, which may be in the shape of an oval ball, which, when turned under rod K, forces the notched head N of said rod K 55 into and against the notched periphery of head E, to which the last C is attached, thereby holding said last in any position required.

F, Fig. 1, is a handle to eccentric L, reaching outside of the stand A, and in a convenient 60 position to be turned by the foot of the operator.

P is a bolt through ears D D and head E.

Q Q, Fig. 2, are guides to steady and keep 65 rod K in position.

S is a shoulder, upon which the lower end of flange R rests.

Fig. 3 also shows the last C provided with beveled lug H inserted into beveled notches m in head E. This head is provided with a 70 circular flange, R, fitting on ears D D and sliding down in front sufficient to rest upon a shoulder, S, in stand A, for the purpose of making a more solid foundation for receiving 75 shocks from the act of working upon the lasts as a greater precaution against bouncing while hammering upon last C. There may be square or rounded projections on lug H fitting into slots in the bottom of notch in head E, as shown on an enlarged scale in Fig. 4 at 80 n n.

What we claim, and desire to secure by Letters Patent of the United States, is—

1. The combination of head E, provided with notches J and beveled notch m m, last 85 C, provided with beveled lug H, rod K, provided with head N, having corresponding notches to notches J, with eccentric L, provided with handle F, substantially as described and set forth.

2. The combination, in an iron last-stand, of a head provided with beveled notch m m, projections or shoulders O O, and detachable last C, provided with cleated lug H, with ears D D, substantially as described and set forth. 95

3. The combination of stand A, provided with guides Q Q, rod K, provided with notched head N, and eccentric L, provided with handle F, with last C, provided with lug H, substantially as described. 100

4. The combination of stand A, provided with ears D D, rod K, provided with notched head N, eccentric L, provided with handle F, and head E, provided with notches J, with last C, provided with lug H, as described and set forth.

5. The combination of stand A, rod K, eccentric L, and oscillating head E, as described, with detachable last C, provided with cleated lug H, as set forth.

6. In combination with stand A, provided

with guides Q Q, rod K, provided with notched head N, and eccentric L, provided with handle F, the oscillating head E, and detachable last C, dovetailed together by cleated notches m m n n, and cleated lug H, substantially as described and set forth.

JAMES K. DUGDALE.
CORNELIUS E. MASTIN.
